UNITED STATES PATENT OFFICE.

EDWARD W. PELTON, OF SPRINGFIELD, MASSACHUSETTS.

AUTOMATIC SWITCH FOR FUSE-WIRES IN ELECTRIC CIRCUITS.

SPECIFICATION forming part of Letters Patent No. 712,204, dated October 28, 1902.

Application filed November 30, 1901. Serial No. 84,179. (No model.)

To all whom it may concern:

Be it known that I, EDWARD W. PELTON, a citizen of the United States of America, residing at Springfield, in the county of Hampden and State of Massachusetts, have invented 5 new and useful Improvements in Automatic Switches for Fuse-Wires in Electric Circuits, of which the following is a specification.

This invention relates to the construction 10 of electric circuits in which a fusible section is incorporated to protect the line from an excessive current; and the invention is directed to the provision of means whereby when by reason of an excess of current on a 15 line a fusible section thereof is burned out an automatically-operating device is set in motion whereby the break made in the line by the destruction of the fuse may be closed and the circuit reestablished.

20 A further object of the invention is to provide means whereby the reestablishment of said circuit may be more or less retarded; and still another object is to provide means whereby the devices operating to reestablish the 25 circuit through a new fusible section may also act to automatically cut out another part of the line—as, for instance, in telephone-circuits, to automatically cut out the well-known carbon-protector situated between the fuse- 30 wire and the instrument and bring into the circuit which includes the new fuse a protector which has not been used.

With these ends in view the invention consists in the construction of the apparatus, 35 which is fully described in the following specification and pointed out in the claims.

The drawings forming part of this application comprise Figure 1, which is in the nature of a diagrammatic view and illustrates 40 the application of my invention in its simplest form to an electric circuit. Fig. 2 is a perspective view of the automatic device whereby a broken circuit is reestablished through another fuse-wire. Fig. 3 illustrates 45 the apparatus shown in Fig. 1 as applied to a somewhat-different circuit, the instrument in this case having a double function. Fig. 4 is a somewhat-enlarged view of the apparatus which is embodied in my invention, 50 showing the form thereof which is adapted to operate a double switch and having applied thereto a device for retarding its movement.

Fig. 5 illustrates the device in another position. Fig. 6 is a plan view of Fig. 4.

The above-referred-to drawings show my 55 invention in a form more particularly adapted to use on telephone-circuits than any other, and in the following specification the description thereof will be confined to its use in this connection; but it may be stated here that 60 its use is not restricted to telephone-circuits, but is applicable to many other electric circuits in which fusible sections are located for the protection of the line and which it may be desirable to replace automatically. 65

In telephone-circuits the practice is, as is well known, to insert a fuse-wire in the line for the protection thereof and for the protection of the building in which the instrument may be located, which fuse-wire, by giving 70 way under an abnormal electric current coming in on the line, will cut off that part of the line beyond it. When this occurs, it is necessary to send a workman to insert a new fuse-wire in the line to reestablish the circuit. 75

By means of my invention I provide in each line several fuse-wires instead of one and automatically-operating devices operable by the rupture of one fuse-wire to reestablish the circuit through another, this 80 other when ruptured operating to set in motion another device like the first to reestablish the circuit through still another fuse-wire. The number of fuse-wires may be as great as desired. 85

In carrying out my invention let it be assumed that the wires *a* and *b* are portions of the same circuit, between which connection is made through a fusible section. In a telephone-circuit these fusible sections would be 90 in the form of a wire (indicated by *c*) which is attached by one end to the wire *a* and by its opposite end to an arm *d*, which is pivotally supported at *e*. From the hub of this arm *d* a wire *f* extends to the part *b* of the 95 line. The connection, therefore, from *a* to *b* of the line will be through the fuse-wire *c*, the arm *d*, and the wire *f*.

There is pivotally supported, as at *g*, an arm *h*, whose free end is hook-shaped, as at 100 *i*, and the point of which engages beneath a flattened section of the hub of the arm *d* in such manner that a suitable spring—as *j*, for instance—may be made to put upon the fuse-

wire *c* a certain tension, whereby it is held taut, said fuse-wire preventing the escape of the hooked end of the arm *h* from engagement with the hub of the arm *d*. In Figs. 1 and 2 this position of the parts is shown. On the arm *h* there is located a metal wedge-shaped piece *k*, which is adapted to enter between the points of the switch *l*, the members of which switch constitute the terminals of a safety connection extending between the parts *a* and *b* of the line and including a new fuse-wire.

From the above description it is seen that the rupture of the first of the fuse-wires *c* breaks the connection between *a* and *b*. The connections through all of the remaining fuse-wires between *a* and *b* are normally broken at the switch *l*, which is located in each. Said switches are so situated that when the arm *h* is released, as by the breaking of a fuse-wire, its spring *j* will cause it to describe a half-circle and drive the wedge *k* between the points of the switch, thus completing a new connection through the fuse-wire situated next to the one which is ruptured. A glance at Fig. 1 (starting from the bottom) will show that while the connection from *a* to *b* is established through the first fuse-wire, the arm *d*, and the wire *f*, no switch is included, but the switch *l* for the second fuse-wire is located in position to be engaged by the arm which is operated by the breaking of the first fuse-wire. The connection through the second fuse-wire would be through the wire *c*, the arm *d*, and a wire *m*, extending to the part *b* of the line, but interrupted by the switch *l*. When a series of these arms are set upon a board, the bottom line *f* will not run through a switch *l*, and the last fuse-wire will not be connected to an arm *d*, but simply to a post *n*, from which connection will be made with the switch *l* by a wire *m*, as in the construction intermediate of the top and bottom fuse-wires. It will be observed that in a circuit constructed in this way no current passes through the arm *h*, but only through the switch-plug thereon when the latter is in connection with the switch *l*, and good connections are thus made possible throughout.

It must be borne in mind that this invention does not run to any particular type of apparatus illustrated or described in this application, for there are many ways other than those shown herein whereby the breaking of the wire might operate a device to reestablish the circuit through another wire; but the type of instrument shown herein is thought to be well adapted to the purpose.

In telephone-circuits the fuse-wires have but little tensile strength, and by making the hooked end of the arm *h* of such shape that it may bear only a little to one side of the axis of the arm *d* but very little tension will thereby be put upon the fuse-wire by the actuating-spring *j* of said arm; but however slight that tension said spring will operate upon the breaking of the fuse-wire to rotate

the arm on its axis to effect the release of said arm *h*. It is desirable, further, that there shall be an appreciable lapse of time between the breaking of one fuse-wire and the reestablishment of the circuit through another, to the end that several of the wires may not be blown out in succession by a too-rapid reestablishment of the circuit before the line had been cleared through its ground connection of its excess of current, and it is thought that the time occupied by the arm *h* in traveling through a half-circle will provide for the necessary lapse of time between the breaking and the reestablishment of said circuit. This period may be lengthened, if desired, or shortened by increasing the distance the arm *h* must travel or by other means, which will be referred to farther on.

In Fig. 3 there is illustrated a circuit which includes that shown in Fig. 1, but which has in addition thereto an auxiliary circuit, whereby the carbon-protector (indicated in this figure by *o*) may be cut out of a line and an unused one brought into the new circuit which is established upon the breaking of a fuse-wire. This carbon-protector, as is well known, is located beyond the fuse-wire and is for the purpose of grounding any excess of current which may pass over the fuse-wire before the rupture of the latter. The method of constructing this circuit is as follows: The circuit shown in Fig. 1 is all included in Fig. 2, the letters of reference being the same, the running of the circuit, however, varying a little between the switches *l* and the part *b* of the line, as follows: Starting from the bottom the circuit is first established between the parts *a* and *b* of the line, the same as in Fig. 1, except that the wire *f* instead of running directly to the part *b* of the line has connected into it, as shown, the protector *o*, from which the wire *p* extends to a second switch *q*, through which normally the current passes onto the line *b*. From the protector *o* the ground-line *r* is taken off in the usual manner. The arm *h* in this construction is provided with the switch-plug *k*, of metal, as in the before-described construction, having thereon a tip *s* of some non-conducting material. Assuming now the wire *c* to be ruptured, the arm *h* will be thrown over to bring the plug *k* into contact with the switch *l* and to force the tip *s* of said plug between the two extremities of the switch *q*, thereby breaking the continuity of the line *f* through the protector *o* to the line *b*; but the plug *k* establishes a line through a new carbon-protector and the second fuse-wire *c* because of the connection between the switches *l* and said part *b* of the line, which connections include a new protector *o* and another switch *q*. It is therefore apparent that the arm *h* may have the double function of cutting in a new carbon-protector and reestablishing a circuit through a new fuse-wire by means set in operation by the rupture of another fuse-wire.

Figs. 4, 5, and 6 show a construction simi-

lar to that in Fig. 3 in two positions in side elevation and also in plan view in one of those positions and include all of the operative devices shown in said Fig. 3 on a somewhat larger 5 scale and shows means whereby the reestablishment of a new circuit upon the interruption of an established circuit may be very considerably retarded. These means consist in forming on the hub of the arm *h* a segmental 10 rack, the teeth of which engage a pinion *u*, on whose shaft there is a fan *v*. This, owing to the resistance of the air, will retard the speed of the arm *h* to such a degree as may be necessary to give the proper time to its movements. 15

By the use of the within-described invention a great saving of labor is effected in maintaining electric circuits in operative condition, and it applies especially to telephone- 20 circuits. By means of this invention each telephone may be provided with a sufficient number of fuse-wires to last for a long time.

Another advantage which may be derived from the use of the invention lies in the fact 25 that if it is found that a telephone-circuit is in bad working order owing to the deterioration of the carbon-protector, whereby the sounds transmitted become more or less blurred, it is possible where an instrument is fitted with a 30 plurality of carbon-protectors as well as with fuses to make an instantaneous connection between the line and some source of electricity having a sufficiently high voltage to rupture one of the fuses to thus switch in a new fuse 35 and a new carbon-protector, as described herein, from the exchange-office. Where telephones are situated, as they are in many cases, at considerable distances from the exchange office, it is very desirable to be able to make 40 this change in the manner stated and avoid the necessity of sending a man to the telephone to do it, as is now the case.

Having thus described my invention, what I claim, and desire to secure by Letters Patent of the United States, is— 45

1. In an electrical circuit, a series of successively-arranged safety connections between the two parts of the line, each including a fusible section and a switch, and a fuse-restrained trip for each switch, substantially as set forth.

2. In an electrical circuit, a fusible safety connection between the two parts of the line, and other successively-arranged similar connections each including a fusible section and a normally open switch, and a circuit-controlling device for each safety connection comprising a self-acting switch-closer, and separate means for restraining the closer and holding the fusible section at a light tension, substantially as set forth. 55

3. In an electrical circuit, a fusible safety connection between the two parts of the line, other successively-arranged similar connections each including a fusible section and a normally open switch, and a circuit-controlling device associated with each safety con- 60

nection and comprising a self-acting switch-closer, and separate means, interposed between the switch-closer, and the fusible section, for restraining the former and holding the latter at a light tension, substantially as set forth. 70

4. In an electrical circuit, a fusible safety connection between the two parts of the line, other successively-arranged similar connections each including a fusible section and a normally open switch, and a circuit-controlling device associated with each safety connection and comprising a self-acting spring-actuated circuit-closer, and separate fuse-restrained means for normally restraining the switch-closer, substantially as set forth. 75

5. In an electrical circuit, a fusible safety connection between the two parts of the line, other successively-arranged similar connections each including a fusible section and a normally open switch, and a circuit-controlling device associated with each safety connection and comprising a self-acting spring-actuated switch-closer, and separate means, interposed between the said closer and the fusible section, for restraining the former and holding the latter at a light tension, substantially as set forth. 80

6. In an electrical circuit, a fusible safety connection between the two parts of the line, other successively-arranged similar connections each including a fusible section and a normally open switch, and a circuit-controlling device associated with each safety connection and comprising a fuse-restraining trip member, and a switch-closer releasable from said trip member and coöperating with the open switch of the next succeeding safety connection, substantially as set forth. 95

7. In an electrical circuit, a fusible safety connection between the two parts of the line, other successively-arranged similar connections each including a fusible section and a normally open switch, and a circuit-controlling device associated with each safety connection and comprising a fuse-restrained trip member, and a self-acting spring-actuated switch-closer releasable from said trip member and coöperating with the open switch of the next succeeding safety connection, substantially as set forth. 100

8. In an electrical circuit, a fusible safety connection between the two parts of the line, other successively-arranged similar connections each including a fusible section and a normally open switch, and a circuit-controlling device associated with each safety connection and comprising a pivotal fuse-restrained trip member and a pivotal self-acting switch-closer releasable from said trip member and coöperating with the open switch of the next succeeding safety connection, substantially as set forth. 115

9. In an electrical circuit, a fusible safety connection between the two parts of the line, other successively-arranged similar connections each including a fusible section and a

normally open switch, and a circuit-controlling device associated with each safety connection and comprising a fuse-restrained pivotal trip-arm having a hub-section, and a spring-
5 actuated swinging switch-closing arm having a hook whose point engages said hub-section at one side of the axis of the trip-arm, substantially as set forth.

10. In an electrical circuit, a fusible safety connection between the two parts of the line, other successively-arranged similar connections each including a fusible section and a normally open switch, and a circuit-controlling device associated with each safety connection and comprising a fuse-restrained pivotal trip-arm having a flattened hub-section, and a spring-actuated pivotally-supported switch-closing arm carrying a contact-plug and provided at its swinging end with a hook
15 whose point is adapted to engage the hub-section at one side of the axis of the trip-arm, substantially as set forth.

11. In an electrical circuit, the main circuit having auxiliary connections including carbon-protectors, a fusible cut-out mechanism comprising means for cutting a new fuse and carbon-protector into the circuit and simultaneously cutting out the carbon-protector associated with the ruptured fuse, substantially as set forth.

12. In an electrical circuit, the main circuit having a series of auxiliary connections including carbon-protectors, a fusible cut-out mechanism including a succession of safety
20 or cut-out connections and comprising means
25

for cutting a new fuse and carbon-protector into the circuit, and simultaneously cutting out the carbon-protector associated with the ruptured fuse, substantially as set forth.

13. In an electrical circuit, the main circuit 40 having a series of auxiliary connections including carbon-protectors, a fusible safety or cut-out connection between the two parts of the line, other successively-arranged similar connections each including a fusible section 45 and a normally open switch, and means associated with each safety connection for simultaneously closing the circuit through the switch of the next succeeding section and cutting out the carbon-protector associated 50 with a ruptured fuse, substantially as set forth.

14. In an electrical circuit, the main circuit having a series of auxiliary connections including carbon-protectors, each of said auxiliary connections having a normally closed switch, a fusible safety or cut-out connection between the two parts of the line, other successively-arranged similar connections each including a fusible section and a normally open 55 switch, paired with one of said normally closed switches, and a single switch-controller associated with each pair of switches to provide for simultaneously closing the circuit through one and breaking it through the 60 other, substantially as set forth.

EDWARD W. PELTON.
